DESIGN FOR A COAT

Moris Revitz, New York, N. Y.

Application May 20, 1940, Serial No. 92,464

Term of patent 3½ years

To all whom it may concern:

Be it known that I, Moris Revitz, a citizen of the United States of America, residing in the city of New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The characteristic feature of my design resides in the combination on the specific coat disclosed of the specific rear shoulder yoke in association with the rear belt and dart arrangement, as shown.

I claim:

The ornamental design for a coat, as shown and described.

MORIS REVITZ.
